United States Patent Office.

GEORGE WILKINSON, OF PROVIDENCE, RHODE ISLAND, ASSIGNOR TO THE GORHAM MANUFACTURING COMPANY, OF SAME PLACE.

Design No. 2,998, dated April 7, 1868.

DESIGN FOR A FORK OR SPOON-HANDLE CALLED "POMPEIAN."

The Schedule referred to in these Letters Patent and making part of the same.

TO ALL WHOM IT MAY CONCERN:

Be it known that I, GEORGE WILKINSON, of the city and county of Providence, and State of Rhode Island, have originated a new Design for Articles of Silver, and other metals and plated ware, of which the following is a full, clear, and exact description, reference being had to the accompanying specimens or drawings, making part of this specification; that is to say, for a design called the "Pompeian," for the handles of spoons, forks, and other table-ware and implements, of which—

Figure 1 represents the front side of the said design, and

Figure 2 represents the back side of the same.

Similar letters indicate corresponding parts in both the figures.

The said design is of a flat handle, with a curved tapering stem, *h*, terminating in a head-shaped plate, *s*, from which the handle gradually widens into the blade *m*, the end of which terminates with the outline of two scrolls, *b b*, and the knob or centre of the Grecian ornament, *f*, which embellishes the front side of the handle.

The edge of this handle is ornamented on both sides with beads or threads *r*, and the said head-shaped plate *s* is ornamented in front with a shell or similar ornament.

On the back side, fig. 2, there is a Grecian scroll, *v*, at the end of the handle, with scroll ornaments on the head-shaped plate *s*, and an ornament of a Grecian honeysuckle, *h*, at the junction of the handle with the bowl of the spoon or other implement.

Claim.

I claim the design for the handles of spoons, forks, and other table-ware and implements, substantially as set forth and shown.

GEO. WILKINSON.
